UNITED STATES PATENT OFFICE.

JOSEPH LETOURNEAU, OF ST. CATHARINES, ONTARIO, CANADA.

PERMUTATION LOCK.

Application filed February 26, 1925. Serial No. 11,855.

To all whom it may concern:

Be it known that I, JOSEPH LETOURNEAU, a subject of the King of Great Britain, residing at St. Catharines, Province of Ontario, Canada, have invented certain new and useful Improvements in Permutation Locks; and I do hereby declare that the following is a full, clear, and exact description of the invention, such as will enable others skilled in the art to which it appertains to make and use the same.

The present invention pertains to a novel permutation lock adapted for application to automobile steering wheels, safe doors and other purposes requiring a lock.

The device comprises a casing in which are mounted lock bolts and slide bolts. The former are designed to penetrate the casing and project into the exterior surrounding element. The slide bolts, although not passing to the exterior of the casing, oppose movement of the lock mechanism except when it is set to the proper combination.

The setting means includes for each lock unit a rotatable disk normally obstructing a slide bolt but having a notch which may receive the bolt. The notch can be placed in the path of the slide bolt only if the combination is known. Through the disk is passed a spindle carrying a ratchet wheel, the latter having a plurality of apertures any one of which may receive a set pin projecting from the disk. The relative position of the ratchet with respect to the disk depends on the particular aperture receiving the set pin. This relation determines the combination, and the latter may be altered by changing the relation. The spindle carrying the ratchet wheel has a pointer co-operating with a dial plate closing the casing, thereby providing an indicator showing the extent that the ratchet is turned.

The bolts carry pins which normally engage cam edges cut in a superposed control ring. When the ring is shifted, the bolts are actuated and are moved inwardly of the casing during the proper shifting of the control ring when the disks are set to present the notches to the slide bolts.

For each unit of the lock, a rocker is pivoted to the casing and normally engages a cam formed with the corresponding disk. The rocker is formed with a guard, normally disposed over the ratchet to prevent shifting of the latter with reference to the disk.

When the disks are set in a given position and the control ring shifted, the relation between each cam and its rocker is such as to move the guard away from the ratchet and thus permit the latter to be raised with reference to its disk whereby the relation between the ratchet and disk may be changed by causing a different aperture to receive the set pin.

The control ring has pivoted thereto a pawl arm for each ratchet and normally locking the latter by virtue of a spring acting on the arm. The spindles, however, are surrounded by coil springs adapted to bring them to zero position when the ratchets are not engaged by their respective pawls. A finger projects upwardly from each pawl arm, and upon the control ring is rotatably mounted a zeroizing ring having cam edges engaging the fingers. By actuation of the control ring, the fingers are moved to bring the pawls away from the ratchet whereupon the springs surrounding the spindles are free to return the ratchets and disks to zero position.

The invention is fully disclosed in the following description and in the accompanying drawings in which:

Figure 1 is a plan view of the device;

Figure 2 is a diametrical section of an automobile steering wheel showing in elevation the lock applied thereto;

Figure 3 is a plan view corresponding to Figure 2;

Figure 4 is a fragmentary elevation of a safe door showing the lock of the invention applied thereto;

Figure 5 is a fragmentary section of a modification;

Figure 6 is a fragmentary section of the device showing the lock bolts projected;

Figure 7 is a similar section showing the parts in intermediate or neutral position;

Figure 8 is a sectional view taken directly beneath the cover and showing the zeroizing ring;

Figure 9 is a detail corresponding to Figure 8 and showing the zeroizing ring shifted;

Figure 10 is a perspective view of the pawl arm;

Figure 11 is a fragmentary transverse section through the wall of the lock casing and showing the manner of assembly;

Figure 12 is a detail edge view of the

zeroizing plate, showing in elevation the stem thereof;

Figure 13 is a sectional view taken on the same plane as Figures 6 and 7 and showing the lock bolts withdrawn;

Figure 14 is a similar section in the same plane and showing the parts in the position permitting the change of combination;

Figure 15 is a plan view of the control 10 ring;

Figure 16 is a section corresponding to Figure 14, and taken at a lower level;

Figure 17 is a perspective view of the 15 guide lip arm;

Figure 18 is a perspective view of the rocker; and,

Figure 19 is an extended section on the line 19—19 of Figure 14.

Reference to these views will now be made 20 by means of like characters which are employed to designate corresponding parts throughout.

The lock is for the most part contained 25 in a circular casing consisting of a base 1 having a circular wall 2 near the edge thereof. This formation leaves a rim 3 outside the wall 2, as shown in Figure 1. The wall is surrounded by an element 4 adapted 30 for penetration by the locking bolts of the device. An inner ring 5 (Figure 16) is formed integral with the base and spaced inwardly of the wall 2 to leave an annular channel 6.

Within the casing is contained a number 35 of locking units. Since these are identical in formation and operation, a description of the parts and operation of one of them will suffice. Each unit comprises a spindle 7 (Figure 7) rotatably inserted in the base and standing upright with reference thereto. The lower end of the spindle carries a loose disk 8 having a keeper slot or notch 9 in its edge. On the lower face of the disk is formed a cam 10 (Figure 16), and the 40 upper face is formed with an integral spacing washer 11 having its periphery in line with the seat of the notch 9. On the upper face of the disk stands also a set pin 12. The spindle carries also a ratchet wheel 13 fixed thereto near the upper end thereof and having a series of peripheral apertures 14 any one of which is adapted to receive the pin 12. Adjacent the spindle a rocker 45 15 (Figure 18) is pivoted to the base. One arm of the rocker is in engagement with the cam 10 and the other arm is provided with a right angular guard 16 which normally lies over the ratchet 13 and prevents it and the spindle 7 from slipping upwardly.

The inner ring 5 is formed with a number 50 of slots 17 with which the notches 9 in the disks 8 are adapted to aline. Slide bolts 18 are adapted to move in these slots and through similar slots 20 cut in the wall 2. Intermediate the slots 17 are cut slots 21

in the ring 5. These contain the locking bolts 22 which pass through alined slots 23 in the wall 2 and into similar recesses 24 in the outer element 4. The bolts 18 and 22 carry at their forward ends pins 18' and 22' respectively.

A control ring 25 (Figure 15) rests on the top of the ring 5 extending to the wall 2 and covering the annular channel 6. This ring is provided with a stem 26 by means 75 of which it may be shifted circumferentially. For each unit of the lock, the inner edge of the ring has a peculiar formation including a lug 27. Substantially midway between the two lugs is a stop 28. The pins 18' on the sliding or intermediate bolts 18 are received in the spaces between the members 27 and 28, following the ring in a counter clockwise direction, and the pins 22' of the locking bolts 22 lie in the spaces between 85 the members 28 and 27. Each space for an intermediate bolt pin includes a release seat 29 at the inner end of the lug 27, a similar intermediate seat 30 nearby, and a cam edge 31 between the seat 30 and a lock seat 32 95 at the foot of the stop 28. The spaces for receiving the lock bolt pins each include a release seat 33 at the other side of the stop, a receding cam edge 34 terminating in a lock seat 35 at the foot of the lug 27.

For each unit of the lock there are a pair of apertures 36 and 37 cut through the ring, the former being formed in the stop 28 and the latter beneath the cam face 34. At the slot 36 the guide arm 38 is pivoted to the ring by means of the screw 38'. At the aperture 37 a pawl arm 39 is pivoted by a screw 39'. The guide arm extends along the cam edge 31, and the pawl arm extends into the space between two of the ratchets. 105 It is formed at its forward end with a pawl 40 normally engaging the corresponding ratchet. Near the rear end thereof is a finger 41, the purpose of which is described below. The guide arm 38 has a depending 110 lip 42 which overlaps the cam edge 31. The lip is slightly shorter than the arm, leaving a recess 43 adjacent the inner extremity of the arm. Around each screw 38' is wound a spring 44 having one end in engagement 115 with the lower portion of the finger 41 and the other end bearing against the guide arm 38 at the recess 43. This arrangement normally holds the lip 42 firmly against the cam edge 31 and the pawl 40 in engagement 120 with the ratchet 13.

At the center of the bottom 1 stands a boss 45 through which is passed a supporting bolt 46. The boss is surrounded by an anchor plate 47 to which are secured the 125 ends of coil springs 48 wound around the spindles 7, the remaining ends being secured to the spindles, as shown in Figure 19. Over the ring 25 is laid a zeroizing ring 49 having a notch 50 and cam edge 51 for each 130

unit of the lock. The notches receive the fingers 41 carried by the pawl arms 39. The ring also has a stem 52 by means of which it is shifted. The ring is formed with a slot 53 through which the stem 26 passes, and which also allows shifting of the zeroizing ring with reference to the control ring. The parts are covered by a dial plate 54 through which the stems 7 pass. Screws 54' (Figure 11) are passed through the plate 54, rings 49 and 25, and finally into the bottom 1 for holding the parts in position. These screws are flattened as at 54" to permit movement of the rings 25 and 49. The exterior end of each stem has secured thereto a pointer 55 and knob 56. On the dial plate a series of numerals surrounds each knob, running from 1 to 9 and having a stop 57 interposed between the 9 and the 1. The plate also has a pair of slots 58 and 59 for receiving the stems 26 and 52 and for permitting shifting of the corresponding rings.

The movements of the lock are as follows: The bolts 18 and 22 are normally urged outwardly by bent springs 60 having their ends received in two bolts 18 and 22 and their midpoint held by a pin 61 in the channel 6. It is to be noted that one leg of the rocker 30 is disposed between a slide bolt 18 and a spindle 7. Assuming that the bolts are projected, as in Figure 6, the pins 18' are disposed in the lock seats 32 behind the recesses 43, and the lock bolt pins 22' are in the lock seats 35. The rocker 15 is engaged by the higher portion of the cam 10, as shown in dotted lines, whereby the guard 16 is held over the ratchet 13 and prevents it from rising with reference to the disk 8. The control ring may now be shifted by actuation of its stem 26, since the inward movement of the bolts following from the action of the cam edges on the respective bolt pins is not obstructed. The pin 18' will be engaged by the cam edge 31 and will lie behind the lip 42. The pin 22' will be engaged by the cam edge 34. If the ring 25 is shifted only sufficiently to bring the pins 18' into the intermediate seats 30, as in Figure 7, the lock is now in neutral position. This means that the ring can be further shifted in the same direction to effect complete opening or in the opposite direction to return it to the position shown in Figure 6 in case the operator decides not to open the lock. The position of parts after the continued and completed movement of the ring in the same direction is illustrated in Figure 13. Here the pins 18' are received in the release seats 29, and the pins 22' are on the release seats 33. In order to project the bolts again the combination is set. The combination which will permit opening of the lock, or retraction of the bolts, is determined by the relation between each ratchet

13 and its disk 8, i. e., the particular aperture 14 in the ratchet that receives the set pin 12 on the disk. The combination being known with reference to the numbers on the dial plate, the knobs 56 are turned to bring the pointers 55 to register with the proper numbers whereby the notch 9 in each disk is brought in alinement with its corresponding slot 17 in the ring 5. The control ring is shifted in the direction opposite to that already mentioned. During this movement the pins 18' ride on the lips 42 and the slide bolts 18 are forced into the notches 9, as shown in Figure 14. Only in this movement do the slide bolts 18 enter the notches 9 in order to allow the pins 18' to shift under the action of the lips 42. Finally, the pins 18' drop from the lips into the recesses 43 and upon the seats 32 whereby the position shown in Figure 6 is restored.

If the combination is to be changed, the control ring 25 is shifted nearly to the position which allows projection of the bolts. This is shown in Figure 14, wherein each pin 18' engages its corresponding lip 42 near the inner edge thereof. In this position, the rocker 15 is held in engagement with the lower edge of the cam 10 by means of the bolt 18. The guard 16 is thus brought away from the ratchet and permits the latter to be raised with reference to its disk 8. The relation between each ratchet and its disk may now be changed.

The springs 48 are so adjusted as normally to hold the pointers 55 in engagement with the stops 57. This may be called the zero position. If, during the operation of the lock, it is desired to cancel the movements already made and to return the parts to zero, this function may be attained by means of the zeroizing ring 49. The latter is shifted in a clockwise direction, as shown by the arrow in Figure 9. The fingers 41 of the pawl arms 39 are pushed inwardly because of the movement of the cam edges 51 along them. Consequently the pawl arms 39 are swinging on their pivots and the pawls 40 withdrawn from the ratchet wheels, whereby the springs 48 are free to return the latter to zero position.

In the construction shown in Figures 2 and 3, the element 4' containing the lock is the hub of an automobile steering wheel 65. The lock is keyed to the steering post 66, and the latter can be turned only when the bolts are projected into the hub 4'. As the lock is in release position, with the bolts retracted, the steering wheel will rotate loosely around the lock and not affect the steering post.

Figure 4 illustrates the invention applied to the door 67 of a safe. The outer element 4" has a plurality of gear teeth 68 engaging slidable racks 69 inserted in the door and adapted to enter the wall 70. When the bolts are retracted, the element 4" may be

rotated by turning the handle 71 which actuates a pinion 72 meshing with internal teeth 73 formed in the member 4". Further rotation of the latter moves the racks 69 inwardly and allows the door to be opened.

Figure 5 shows a modification in which the combination can be changed only from the inside of the safe or the like. The advantage of this construction is that the mechanism for changing the combination is not normally exposed. In this instance the spindle 7' has its inner end squared as at 74. An extension 75 is slidable on the squared end and carries a knob 76 at the inner side 15 of the lock. The end of the extension within the lock carries the ratchet 13'. The latter can be separated from the set pin 12' for changing the combination only by pushing the knob 76 towards the lock.

20 While specific embodiments of the invention have been illustrated and described, it is to be understood that various alterations in the details of construction may be made without departing from the spirit of the invention as indicated by the appended claims.

Having thus fully described the invention, what I claim as new and desire to protect by Letters Patent is:—

30 1. A permutation lock comprising a casing, bolts slidable therethrough, disks obstructing some of said bolts, said disks being formed with notches adapted to admit said obstructed bolts, and a control ring adapted to actuate said bolts.

35 2. A permutation lock comprising a casing, lock bolts slidable therethrough, slide bolts slidable therein, disks obstructing said slide bolts, said disks being formed with notches for receiving said slide bolts, and a control ring for actuating said bolts.

40 3. A permutation lock comprising a casing, bolts slidable therethrough, disks obstructing some of said bolts, said disks being formed with notches adapted to admit said obstructed bolts, pins carried by said bolts, and a shiftable control ring having cam edges engaging said pins.

45 4. A permutation lock comprising a casing, lock bolts slidable therethrough, slide bolts slidable therein, disks obstructing said slide bolts, said disks being formed with notches for receiving said slide bolts, pins carried by said bolts, and a shiftable control ring having cam edges engaging said pins.

50 5. A lock unit comprising in a casing, a lock bolt slidable therethrough, a slide bolt slidable therein, a spindle rotatably supported in said casing, a ratchet carried by the spindle, means movable with said spindle for obstructing said slide bolt, a control ring for actuating said bolts, and a pawl pivoted to said ring and normally engaging said ratchet.

55 6. A lock unit comprising in a casing, a lock bolt slidable therethrough, a slide bolt

slidable therein, a disk disposed in the path of said slide bolt, a pin carried by said disk, a spindle passed through said disk and rotatably mounted in the casing, a ratchet wheel carried by said spindle and having a plurality of apertures each of which is adapted to receive the said pin, said disk having a notch adapted to receive said slide bolt, a control ring for actuating said bolts, and a pawl pivoted to said ring and engaging said ratchet.

70 7. A lock unit comprising in a casing, a lock bolt slidable therethrough, a slide bolt slidable therein, a disk disposed in the path of said slide bolt, a pin carried by said disk, a spindle passed through said disk and rotatably mounted in the casing, a ratchet wheel carried by said spindle and having a plurality of apertures each of which is adapted to receive the said pin, said disk having a notch adapted to receive said slide bolt, a control ring for actuating said bolts, 75 a pawl pivoted to said ring and engaging said ratchet, and a guard disposed over said ratchet to prevent the spindle from shifting with reference to the disk.

8. A lock unit comprising in a casing, a lock bolt slidable therethrough, a slide bolt slidable therein, a spindle rotatably supported in said casing, a ratchet carried by the spindle, means movable with said spindle for obstructing said slide bolt, a cam carried by said means, a rocker pivoted to said means, a guard formed with said rocker and disposed over said ratchet to prevent the spindle from shifting with reference to the said means, said slide bolt being adapted to press the rocker into engagement with the cam to move the guard with reference to the ratchet, a control ring for actuating said bolts, and a pawl pivoted to said ring and normally engaging said ratchet.

95 9. A lock unit comprising in a casing, a lock bolt slidable therethrough, a slide bolt slidable therein, a spindle rotatably supported in said casing, a ratchet carried by the spindle, means movable with said spindle for obstructing said slide bolt, a control ring for actuating said bolts, a pawl pivoted to said ring and normally engaging said ratchet, a spring wound around said spindle, said spring having one end attached to the spindle and another end fixed with reference to the casing, said spring being adapted to rotate said spindle and ratchet, and means for moving said pawl out of engagement with the ratchet.

100 10. A lock unit comprising in a casing, a lock bolt slidable therethrough, a slide bolt slidable therein, a spindle rotatably supported in said casing, a ratchet carried by the spindle, means movable with said spindle for obstructing said slide bolt, a control ring for actuating said bolts, a pawl pivoted to said ring and normally engaging 105 said ratchet, and means for moving said pawl out of engagement with the ratchet.

110 11. A lock unit comprising in a casing, a lock bolt slidable therethrough, a slide bolt

115

120 12. A lock unit comprising in a casing, a lock bolt slidable therethrough, a slide bolt

125

125 13. A lock unit comprising in a casing, a lock bolt slidable therethrough, a slide bolt

130

135 14. A lock unit comprising in a casing, a lock bolt slidable therethrough, a slide bolt

said ratchet, a spring wound around said spindle, said spring having one end attached to the spindle and another end fixed with reference to the casing, said spring being adapted to rotate said spindle and ratchet, means for moving said pawl out of engagement with the ratchet, a finger projecting from said pawl, and a zeroizing ring superposed on said control ring and being formed with a cam edge engaging said finger, whereby the pawl is released from the ratchet by actuation of said zeroizing ring.

11. A lock unit comprising in a casing, a lock bolt slidable therethrough, a slide bolt slidable therein, a spindle rotatably supported in said casing, a ratchet carried by the spindle, means movable with said spindle for obstructing said slide bolt, a cam carried by said means, a rocker pivoted to said means, a guard formed with said rocker and disposed over said ratchet to prevent the spindle from shifting with reference to the said means, said slide bolt being adapted to press the rocker into engagement with the cam to move the guard with reference to the ratchet, a control ring for actuating said bolts, a pawl pivoted to said ring and normally engaging said ratchet, a spring wound around said spindle, said spring having one end attached to the spindle and another end fixed with reference to the casing, said spring being adapted to rotate said spindle and

ratchet, and means for moving said pawl out of engagement with the ratchet.

12. A lock unit comprising in a casing, a lock bolt slidable therethrough, a slide bolt slidable therein, a spindle rotatably supported in said casing, a ratchet carried by the spindle, means movable with said spindle for obstructing said slide bolt, a cam carried by said means, a rocker pivoted to said means, a guard formed with said rocker and disposed over said ratchet to prevent the spindle from shifting with reference to the said means, said slide bolt being adapted to press the rocker into engagement with the cam to move the guard with reference to the ratchet, a control ring for actuating said bolts, a pawl pivoted to said ring and normally engaging said ratchet, a spring wound around said spindle, said spring having one end attached to the spindle and another end fixed with reference to the casing, said spring being adapted to rotate with said spindle and ratchet, a finger projecting from said pawl, and a zeroizing ring superposed on said control ring and being formed with a cam edge engaging said finger, whereby the pawl is released from the ratchet by actuation of said zeroizing ring.

In witness whereof I have hereunto set my hand.

JOSEPH LETOURNEAU.
